(57) **CLAIM**

The ornamental design for a portable computer, as shown and described.

DESCRIPTION

FIG. 1 is a right, front, and top perspective view of a portable computer showing my design.

FIG. 2 is a front elevational view of the portable computer in FIG. 1.

FIG. 3 is a rear elevational view of the portable computer in FIG. 1.

FIG. 4 is a left-side elevational view of the portable computer in FIG. 1.

FIG. 5 is a right-side elevational view of the portable computer in FIG. 1.

FIG. 6 is a top plan view of the portable computer in FIG. 1.

FIG. 7 is a bottom plan view of the portable computer in FIG. 1.

FIG. 8 is a right, front, and top perspective view of the portable computer in FIG. 1 in a closed state.

FIG. 9 is a left, rear, and top perspective view of the portable computer in FIG. 1 in the closed state.

FIG. 10 is a partial enlarged view of the portable computer in FIG. 3; and,

FIG. 11 is a partial enlarged view of the portable computer in FIG. 9.

The evenly-spaced broken lines shown in the drawings are included for the purpose of illustrating portions of the portable computer that form no part of the claimed design; the unevenly-spaced broken lines delineate areas of the figures shown enlarged and form no part of the claimed design.

1 Claim, 11 Drawing Sheets
